(57) **CLAIM**

The ornamental design for a duplex receptacle lateral interconnect power adaptor, as shown and described.

DESCRIPTION

FIG. 1 is a top, front and left side perspective view of a duplex receptacle lateral interconnect power adaptor showing my new design;

FIG. 2 is a top, front and right side perspective view thereof;

FIG. 3 is a top, rear and right side perspective view thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof; and,

FIG. 9 is a bottom plan view thereof.

The broken lines in the drawing views represent unclaimed environment and forms no part of the claimed design.
